STONE CUTTING OR BREAKING MACHINE

Alex Ross Patterson, Dallas, Tex.

Application February 21, 1936, Serial No. 65,153

2 Claims. (Cl. 125—23)

The device forming the subject matter of this application is adapted to be used for cutting stone accurately to shape, although the device might be employed for working upon brick, concrete blocks 5 and the like, as well as natural stone.

The usual method of bringing stone to accurate dimensions embodies the use of a drill, for making holes in the stone, wedges then being driven into the holes to force the stone apart.

As distinguished from such a procedure, this invention aims to provide a machine which, through the instrumentality of blades extending all the way across the stone, cuts and wedges the stone apart, without resorting to drilling or 10 hammering.

The invention aims to improve the construction of the frame which carries the working parts, to provide novel means for supporting the stone for vertical adjustment, and to supply novel means 15 for imparting movement, at the will of an operator, to the movable blade.

It is within the province of the disclosure to improve generally and to enhance the utility of devices of that type to which the invention 20 pertains.

With the above and other objects in view, which will appear as the description proceeds, the invention resides in the combination and arrangement of parts and in the details of construction 25 hereinafter described and claimed, it being understood that changes in the precise embodiment of the invention herein disclosed, may be made within the scope of what is claimed, without departing from the spirit of the invention.

In the accompanying drawing:

Fig. 1 shows, in elevation, a device constructed in accordance with the invention;

Figs. 2, 3 and 4 are sections taken, respectively, on the lines 2—2, 3—3 and 4—4 of Fig. 1;

Fig. 5 is a section on the line 5—5 of Fig. 4;

Fig. 6 is a section on the line 6—6 of Fig. 3.

In carrying out the invention, there is provided a frame, including vertical, two-part standards 1, each having a guideway 2. Supporting feet 3 are secured as shown at 4, intermediate their ends, to the lower ends of the standards 1.

At their upper ends, the standards 1 are joined by a top member 5, which may be a composite structure. The top member 5 comprises inner bars 49, the ends of which abut against the inner edges of the standards 1. Intermediate plates 6 overlap the inner bars 49, and the standards 1 are received between the end portions of the plates 6. Outer bars 7 are overlapped on the intermediate 50 plates 6 and are as long as the intermediate

plates. The intermediate plates 6 extend downwardly below the outer plates 7, and the lower edges of the outer plates 7 form shoulders, having functions which will be alluded to hereinafter. The parts 49, 6 and 7 are connected, between the standards 1, by securing elements 8. Securing members 9 connect the end portions of the intermediate plates 6 and outer bars 7 with the standards 1. Braces 10 extend between the outer plates 7 of the top bar 5 and the feet 3, the number of braces employed being left to the discretion of the manufacturer. The top member 5 extends outwardly beyond the standards 1, as Fig. 1 will show, the parts 49, 6 and 7 of the top member 5 being joined by rigid transverse ties 11. 15

Raising and lowering devices 12 are provided, and may be in the form of screws, passing downwardly through the top member 5 and journaled in the ties 11. Operating handles 14 are secured to the upper ends of the screws 12 and have hubs 20 which rest on the ties 11.

The numeral 15 designates, generally, a vertically adjustable deck. The deck 15 embodies bars 16, connected intermediate their ends by securing members 17, the bars 16 being spread 25 apart at their ends to form forks 18 which receive the standards 1 and slide vertically thereon. The forks 18 extend outwardly beyond the standards 1, as can be seen in Fig. 4. The securing members 17 hold a spacer 50 between the bars 16. 30

Between the bars 16 is located a lower blade 19, having a sharpened, inverted, V-shaped, wedge-like upper portion 20. The blade 19 is secured to the bars 16, detachably, by bolts 21 or equivalent means. The ends of the blade 19 are 35 received slidably between the members of the standards 1 (Fig. 4). The lower edge of the blade 19 rests on the spacer 50, as shown in Fig. 5.

Blocks 22 are secured in the forks 18, outwardly of the standards 1, the raising and lowering 40 screws 12 being threaded into the blocks. The bars 16 carry sills 23, which are disposed horizontally and parallel to the feet 3. Platforms 24 are mounted on the sills 23, on opposite sides of the standards 1. The platforms 24 may be freely 45 removable, but the operator may fasten them in place, if he wishes to do so, that being a simple matter requiring no illustration.

A slide 25 is mounted on the frame, for vertical adjustment, above the deck 15, and is a 50 composite structure. The slide 25 may include inner bars 26, having their ends in slidable engagement with the inner edges of the standards 1, outer plates 27 being overlapped on the inner bars 26, the bars 26 and the plates 27 being 55

held together detachably by securing devices 28. The plates 27 extend upwardly above the bars 26. The securing devices 28 retain, between the inner bars 26, an upper or movable blade 29, having a depending, sharpened, V-shaped, wedge-like portion 30.

The means for moving the slide 25 and the blade 29 up and down may be of any desired form. If preferred, the standards 1 may be connected, above the slide 25, by cross pieces 31, in which is journaled a shaft 32 having a squared end 33, providing for the detachable mounting of a laterally extended arm 34. Between the cross pieces 31, the shaft 32 carries a crank disk 35, to which oppositely-extended thrust members 36 are pivoted, as indicated at 37. Toggle mechanisms are provided, and include upper links 38 and lower links 39, the lower ends of the upper links and the upper ends of the lower links being pivoted at 40 to the outer ends of the thrust members 36. The upper links 38 extend between the inner plates 6 of the top member 5 and carry short shafts 41, journaled in the plates 6. The shafts 41 bear against the shoulders formed by the lower edges of the outer bars 7 of the top member 5, and the upper ends of the links 38 bear against the inner bars 49 of the top member 5. Owing to this construction, strain is taken off the plates 6, the said plates constituting merely a journaling means for the shafts 41. The lower ends of the lower links 39 extend between the outer plates 27 of the slide 25 and have shafts 42 journaled in the plate 27. The lower ends of the links 39 abut against the inner bars 26 of the slide 25, and thus strain is taken off the plates 27, those plates constituting merely a journaling means for the shafts 42.

The operation of the device is simple. By means of the operating handles 14, the screws 12 may be rotated thereby raising and lowering the deck 15, to adjust the height of the stone which is to be cut, the stone being supported on the wedge portion 20 of the lower blade 19, which extends a little way above the platforms 25, as shown in Fig. 2, so that the part 20 can have opportunity to act upon the stone which is to

be cut. The stone, of course, may be shimmed up from the platforms 24.

When the arm 34 is swung, the shaft 32 rotates the disk 35, and the thrust members 36, together with the links 38 and 39, carry the slide 25 downwardly, the upper blade 29 being carried downwardly also. The part 30 of the blade 29 and the part 20 of the blade 19 cooperate to incise the stone and wedge it apart, all in one operation and all the way across the stone. It is unnecessary to drill the stone and to separate it by hammer-driven wedges. The machine turns out a neatly shaped article and can be used upon frail stone which cannot be worked otherwise without great waste of material. 15

What is claimed is:

1. In a machine for shaping stone, a frame, a deck carried by the frame, a slide mounted to reciprocate on the frame, toward and away from the deck, means for reciprocating the slide, a blade carried by the slide, a blade carried by the deck, the blades being provided with wedge-shaped stone-cutting and stone-separating edges, the edge of one blade being presented toward the edge of the other blade, means for mounting the deck on the frame, for adjustment toward and away from the slide, and means under the control of an operator for adjusting the deck toward and away from the slide.

2. In a machine for shaping stone, a frame, a deck carried by the frame, a slide mounted to reciprocate on the frame, toward and away from the deck, means for reciprocating the slide, a blade carried by the slide, a blade carried by the deck, the blades being provided with wedge-shaped stone-cutting and stone-separating edges, the edge of one blade being presented toward the edge of the other blade, means for mounting the deck on the frame, for adjustment toward and away from the slide, and means under the control of an operator for adjusting the deck toward and away from the slide, the last-mentioned means embodying screws journaled in the frame and held against longitudinal movement therein, the screws being threaded into the deck and carrying the deck. 40
